(57) **CLAIM**

The ornamental design for a child seat, as shown and described.

DESCRIPTION

FIG. 1 is a top view of the child seat showing my new design;
FIG. 2 is a top perspective view thereof;
FIG. 3 is a front view thereof;
FIG. 4 is a left side view thereof;
FIG. 5 is a right side perspective view thereof;
FIG. 6 is a rear-right side perspective view thereof;
FIG. 7 is a left side front perspective view thereof; and,
FIG. 8 is a bottom-rear-right side perspective view thereof.
The child safety seat for a vehicle of this design has an open
architecture, has a recline mechanism and safety features.
